CIRCUIT BREAKER

Hans H. Willmann, Berlin-Charlottenburg, Germany, assignor to Westinghouse Electric & Manufacturing Company, East Pittsburgh, Pa., a corporation of Pennsylvania

Application August 2, 1937, Serial No. 157,027
In Germany August 3, 1936

6 Claims. (Cl. 200—106)

The invention relates to circuit breakers in general and more particularly to moderate power circuit breakers of the type used for controlling lighting and moderate power industrial distribution circuits.

An object of the invention is the provision of an improved circuit breaker of the above type that is simple, safe and reliable in operation, extremely compact, and which can be manufactured at a relatively low cost.

Another object of the invention is the provision of an improved circuit breaker embodying an electromagnetic means for opening the breaker in response to heavy overloads and short circuit conditions, and a thermal means for opening the breaker in response to moderate overloads of predetermined duration; the electromagnetic means also serving to move and extinguish the arc formed during circuit interruption.

Another object of the invention is the provision of a circuit breaker with an improved electromagnetic means which serves both as a blowout means for moving and extinguishing the arc during circuit interruption and also as a trip means for opening the breaker in response to heavy overloads and short circuit conditions.

Another object of the invention is the provision of a circuit breaker with an improved electromagnetic blowout means for producing a very strong blowout field capable of rapidly moving and extinguishing large arcs in an extremely short period of time, yet which is so arranged together with the other parts of the breaker that the breaker occupies a relatively small amount of space.

Another object of the invention is the provision of a circuit breaker as described in the preceding paragraphs in which the electromagnetic means and other parts of the breaker are arranged in a novel cooperative manner so that the breaker as a whole occupies a much smaller space for a given switching power or provides a greater switching power for a given amount of space occupied by the breaker than has heretofore been considered possible.

The novel features that are considered characteristic of the invention are set forth in particular in the appended claims. The invention itself, however, both as to structure and operation together with additional objects and advantages thereof will best be understood from the following detailed description of one embodiment thereof when read in connection with the accompanying drawings, in which:

Figure 1 is a vertical sectional view of a circuit

breaker constructed in accordance with the invention, the breaker being shown in the open circuit position;

Fig. 2 is a sectional view of the circuit breaker taken at right angles to Fig. 1 on the line II—II thereof;

Fig. 3 is a sectional view similar to Fig. 1 showing the position of the various parts when the circuit breaker is in the closed circuit position;

Fig. 4 is a plan view of the stationary contact 10 and the means for connecting the same to the windings of the electromagnet;

Fig. 5 is a view taken at right angles to Fig. 4;

Fig. 6 is a side elevational view of the movable contact and switch member; and

Fig. 7 is a horizontal sectional view of the movable contact and switch member taken on the line VIII—VIII of Fig. 6.

Referring to the drawings, the circuit breaker embodying the features of the invention comprises a base 9 of ceramic insulating material and a cover 11 therefor, the base and cover forming an enclosing casing for the parts of the breaker. An arc chute 13 also of ceramic insulating material is mounted on the base 9 adjacent the upper end thereof. The arc chute 13 forms an interrupting chamber 15 in which is mounted a stationary contact 17.

A main frame, comprising a base portion 19 and a pair of spaced parallel side plates 21, is mounted within the casing on the base 9. The main frame serves to support a movable switch member indicated generally at 23, and actuating means indicated generally at 25.

The switch member 23 (Figs. 6 and 7) comprises a block 27 of insulating material, a movable contact 29 secured to the upper end of the block by suitable fastening means 31, and a yoke-shaped switch lever 33. The ends of the legs of the yoke-shaped switch lever 33 are rounded as indicated at 35 so as to fit in circular recesses provided in the opposite sides of the insulating block 27. The block 27 is slotted as indicated at 37 at the end opposite that carrying the contact 29, so as to permit the block and contact 29 carried thereby to have a limited rotational movement about the rounded ends 35 of the yoke-shaped switch lever 33. A coil compression spring 39 is disposed between the upper portion of the slotted end of the block 27 and a cross piece 41 which bridges the legs of the yoke-shaped switch lever 33. The spring 39 biases the block 27 in a counter-clockwise direction about its pivot axis formed by the rounded ends 35 of the yoke-shaped switch lever 33, so as to maintain a pre-

5

determined high contact pressure between the movable contact 29 and the stationary contact 17 when the circuit breaker is in the closed circuit position.

- 5 The switch member 23 is pivotally mounted upon the main frame for movement in a plane perpendicular to the base 9 between open and closed circuit position by means of a transverse pivot pin 43 which extends through the side walls 21 of the frame and through an opening 45 provided therefor in the yoke-shaped switch lever 33, the axis of the pivot pin 43 being disposed parallel to the base 9 of the breaker. The pivot mounting of the switch member 23 is such that 15 the path of movement of the movable contact 29 carried thereby is located between the side walls of the arc chute 13 within the interrupting chamber. A flexible shunt conductor 47 consisting of a flat resilient strip of conducting material is 20 secured at one end to the movable contact 29 and serves to conduct current thereto.

The actuating means for the circuit breaker comprises in general a pair of toggle links 49 and 51, a carrier lever 53, a latching or blocking lever 55 for the carrier lever, a closing push button 57 and a releasing push button 59. The upper end of the toggle link 49 is pivotally connected to a projecting portion of the yoke-shaped switch lever 33 by means of a pivot pin 61, while 30 the lower end of the toggle link is pivotally connected to the upper end of the toggle link 51 by means of a knee pivot pin 63. The lower end of the toggle formed by the links 49 and 51 is pivotally connected to the carrier 53 by means of a pivot pin 65, the carrier itself being pivotally supported on the main frame by means of a transverse pivot pin 67. The inner end of the closing push button 57 is provided with a pair of projecting studs 69 which pass through openings 40 provided in lugs 71 carried by the main frame, which serve to guide the push button 57 during movement of the same. The push button 57 is also provided with a plate 73 secured to the underside thereof which has a vertically disposed 45 elongated slot 75 for engaging the knee pivot pin 63 of the toggle linkage. A resilient spring strip 58 secured to the cover 11 serves to bias the push button 57 outwardly to its normal position shown in Fig. 1.

50 The latching lever 55, which serves to support the free end of the carrier lever 53, is pivotally supported on the main frame by means of a pivot pin 77 which extends through the side walls 21 of the main frame. The latching lever 55 is 55 biased to its latched position shown in Figs. 1 and 3 by means of an intermediate lever 79 which is pivoted to the main frame by means of a pivot pin 81 and biased in a clockwise direction by means of a compression spring 83, the spring 83 60 acting through the intermediate lever 79 to bias the latching lever 55 to its latched position.

The release button 59 is connected to the intermediate lever 79 above its pivot 81 by means of a rod 86, so that when the release button 59 is 65 pushed inwardly, the intermediate lever 79 is rotated in a counter-clockwise direction about its pivot pin 81 to move the latching lever 55 also in a counter-clockwise direction about its pivot pin 77 to released position.

70 The manual operation of the circuit breaker is as follows: With the breaker in the open circuit position as shown in Fig. 1, let it be assumed that it is desired to close the breaker. The closing push button 57 is manually depressed by the 75 operator. The inward movement of the closing

push button is transmitted to the knee pivot pin 63 of the toggle by means of the plate 73 and edges of the slot 75 to effect movement of the knee pivot pin toward the left, as viewed in Fig. 1. This movement of the knee pivot pin toward the left by the push button 57 moves the toggle links to the "made" or "in-toggle" position, as shown in Fig. 3. In this position, the knee pivot pin 63 is located slightly to the left of a center line joining the pin 61 and the pin 65. Since the 10 pivot pin 65 which connects the lower toggle link 51 to the carrier 53 is held stationary by reason of the latching lever 55 engaging the carrier 53, the movement of the toggle links 49 and 51 to their "made" position effects rotation of the 15 switch member 23 to the closed circuit position, as shown in Fig. 3. It will be noted that in this closed circuit position of the switch member, the compression spring 39 between the block 27 and the switch lever 33 is held compressed so as to 20 exert a high contact pressure between the movable and stationary contacts. The reaction of this force is transmitted through the switching lever 33 to the toggle links 49 and 51 and tends to maintain them in their "made or toggle position" shown in Fig. 3. The reactive pressure is sufficient to hold the toggle links in their made position against the bias of the return spring strip 58, which biases the closing push button 57 25 in an outward direction.

To open the breaker, the release button 59 is depressed. The depression of the button 59 rotates the intermediate lever 79 in a counter-clockwise direction about its pivot pin 81 against the bias of the spring 83. The counter-clockwise movement of the intermediate lever 79 effects counter-clockwise movement of the latching lever 55 about its pivot pin 77 to release the free end of the carrier lever 53. When the carrier lever 53 is released, the reactive force exerted by the spring 39 is transmitted through the toggle links and causes a slight counter-clockwise movement of the carrier lever 53. The slight counter-clockwise movement of the carrier lever 53 effects movement of the toggle links to their aligned or dead-center position, that is to say, effects a slight movement of the knee pivot pin 63 to the right toward dead-center position. At this point, the force exerted by the return spring strip 58 moves the closing push button 57 in an outward direction to effect collapse of the toggle links 49 and 51. The collapse of the toggle links effects rotation of the switch member 23 to its open circuit position shown in Fig. 1.

Following release of the button 59, the spring 83 acts through the intermediate lever 79 to return the latching lever 55 to its latching position in engagement with the free end of the carrier lever 53, the carrier lever 53 having been previously returned to its normal position by the outward movement of the push button 57 under the influence of the return spring strip 58, so that the breaker is automatically reset for the next circuit closing operation.

A thermal trip means is provided for effecting automatic opening of the breaker in response to moderate overloads of predetermined duration. The thermal trip means comprises a bimetallic strip 85 secured at its lower end to the base 9. 70 The bimetallic strip 85 is connected in series circuit with the contacts 29 and 17, and the free end thereof is provided with a projection 87 which engages a portion of the latching lever 55. When an overload of predetermined value and 75

duration occurs in the circuit controlled by the breaker, the bimetallic strip 85 is heated a sufficient amount to cause it to flex upwardly toward the actuating mechanism. This flexing movement of the bimetallic strip effects rotation of the latching lever 55 in a counter-clockwise direction to its released position to effect opening of the breaker in the same manner as when the release button 59 is depressed. The provision of 5 the elongated slot 75 in the plate 73 carried by the closing push button 57 provides the desirable trip-free action so that the switch member 23 may be moved to open circuit position in response to a tripping operation even though the 10 closing push button 57 is held depressed. After the breaker has been opened, no current flows through the bimetallic strip 85 so that the strip cools and returns to its original position shown in Fig. 1, allowing the spring 83 and intermediate 15 lever 79 to return the latching lever 55 to its latched position to reset the breaker.

An electromagnetic means is provided for the purpose of rapidly moving and extinguishing the arc formed between the stationary and movable 20 contacts 17 and 29 during circuit interruption, and also for the purpose of tripping the breaker to open circuit position in response to heavy overloads and short circuit conditions. The electromagnetic means comprises a pair of coils 89 25 disposed on opposite sides of the interrupting chamber 15 and path of movement of the movable contact. The coils 89 are wound upon and supported by aligned core members 91 of magnetic material, the axis of the coil members 89 30 and the cores 91 being disposed parallel to the base 9 of the breaker and relatively close to the actuating mechanism 25. The inner ends of the core members 91 are provided with pole pieces 93 which lie on opposite sides of the path of movement 35 of the movable contact 29, outside the side walls of the arc chute 13. The two coils 89 produce a strong magnetic blowout field between the pole pieces 93 which traverses the interrupting chamber 15 for rapidly moving and extinguishing 40 the arc formed between the stationary and movable contacts during circuit interruption. The particular arrangement of the two coils 89 on opposite sides of the interrupting chamber with their aligned axes passing through the chamber 45 produces an extremely strong blowout field which is capable of extinguishing large arcs in a very short period of time, thus increasing the switching power of the circuit breaker so that the same 50 is capable of interrupting larger amounts of current.

The electromagnetic means also includes an armature 95 of magnetic material comprising a pair of legs 97 extending on opposite sides of the coils 89 and the actuating mechanism 25. The 55 legs 97 of the armature are pivotally mounted on the transverse pivot pin 43 which forms the pivot axis of the switch member 23. The two legs 97 of the armature are connected by a cross piece 99 which extends beneath the actuating mechanism and serves as a path for the flux produced by the coils 89. The pivot pin 43 which is of magnetic material also carries a part of the flux so that the cross piece 99 and the pivot pin 43 60 both form part of the magnetic circuit of the electromagnetic means. The upper ends of the two legs 97 of the armature extend outside of the outer ends of the two coils 89 to a position adjacent the outer ends of the cores 91, there 65 being only a relatively small air gap between the

upper ends of the legs 97 of the armature and the core members 91.

One of the legs 97 of the armature 95 is provided with an extension 101 which serves to engage and move the latching lever 55 to its released position when the armature is rotated in a counter-clockwise direction about the pivot pin 43 to its attracted position in response to a heavy magnitude overload or short circuit condition.

The magnetic circuit of the electromagnetic means described above extends from the pole piece 93 of the left-hand coil 89 across the interrupting chamber 15 to the opposite pole piece 93, through the core member 91 of the right-hand coil to the right-hand leg 97 of the armature 95, 15 through the cross piece 99 of the armature and the pivot pin 43 to the opposite leg 97, and through the left-hand core member 91 back to the pole piece 93 of the left-hand coil 89.

The stationary contact 17 is secured to the off-set end 103 of a T-shaped conducting member 105. The ends of the cross bar of the T-shaped member 105 serve to connect the stationary contact 17 with the ends 107 of the windings of the coils 89. The windings of the coils 89 consist of flat copper strips 109 which are wound on the core members 91 so as to produce elliptical-shaped coils which have their longer axes parallel to the base 9.

The above-described electromagnetic means 30 and its disposition with respect to the actuating means and interrupting chamber effects a considerable reduction in the space occupied by the breaker. It makes possible a considerable decrease in the construction height of the breaker, 35 so that the same does not extend so far from the switchboard or other fastening surfaces as in the prior art constructions. In addition, the space requirements in the two other main directions are also decreased.

The circuit for the breaker extends from one terminal 111 through a conductor (not shown) to the free end of the bimetallic trip element 85 through the bimetallic trip element 85 through the shunt conductor 47 to movable contact 29 and stationary contact 17, and from the stationary contact 17 in parallel through the windings of the coils 89 to the opposite terminal 113.

It is believed that the operation of the circuit breaker will be readily understood from the above detailed description. The circuit breaker may be closed manually by depressing the closing switch button 57. The depression of the button 57 causes the toggle links to be moved to their "made" position to effect movement of the switch member 23 to closed circuit position in the manner previously described in detail. To open the breaker manually, the release button 59 is depressed. The depression of the release button 59 effects movement of the latching lever 55 to its released position to release the carrier 53. When the carrier is released, the spring 39 moves the toggle links from their made position toward their dead-center position so as to allow the return spring strip 58 to effect collapse of the toggle links and return the closing push button 57 to its normal or open circuit position. The collapse of the toggle links effects movement of the switch member 23 to its open circuit position.

With the breaker in closed circuit position, as shown in Fig. 1, if an overload of moderate magnitude and predetermined duration occurs, the bimetallic strip 85 is heated so as to flex in a direction toward the actuating mechanism 25. This flexing of the bimetallic strip moves the

latching lever 55 to its released position to release the carrier 53. When the carrier 53 is released, the breaker is opened in the same manner as has been previously described in connection with the manual operation.

When a high magnitude overload or short circuit condition occurs in the circuit controlled by the breaker, the armature 95 is moved to its attracted position with the upper ends of its legs 10 against the pole pieces 96. When the armature is moved to attracted position, the extension 101 thereof engages and moves the latching lever 55 to its released position to effect opening of the breaker in the manner previously described.

15 The spring 83 acting through the intermediate lever 79 returns the latching lever 55 to its latched position to reset the breaker following each circuit opening operation.

While the invention has been shown and described in accordance with the provisions of the patent statutes, it is to be understood that various changes may be made in the structural details thereof without departing from the spirit of the invention. It is desired, therefore, that the 25 language of the accompanying claims be given the broadest reasonable interpretation permitted by the prior art.

I claim as my invention:

1. In a circuit breaker, a base of insulating 30 material, a first contact mounted thereon, said base also supporting electromagnetic blowout means for moving and extinguishing the arc drawn at said contact including a pair of pole pieces on opposite sides of said contact, coil 35 means for the pole pieces disposed at the side of said contact with its extended axis transversely crossing the arc path, said base likewise supporting a frame carrying a pivot pin which pivotally supports an armature movable by said electromagnetic means in response to predetermined 40 overload conditions on said circuit breaker, said pivot pin likewise pivotally supporting an arm carrying the movable contact for said circuit breaker, actuating means for said arm pivotally mounted on said frame, said armature when moved in response to said predetermined conditions decreasing the reluctance of the magnetic 45 circuit of said electromagnetic means to increase the blowout action thereof.

50 2. In a circuit breaker, a base provided with an interrupting chamber, a stationary contact in said chamber and mounted on said base, a frame supported on said base and a movable contact pivotally mounted on said frame, said contacts 55 being relatively movable in a plane perpendicular to said base, actuating means for the contacts likewise pivotally mounted on said frame, combined electromagnetic blowout and trip means including a pair of aligned coils disposed on opposite sides of the 60 chamber and plane of movement of the contacts with their axes extending transversely across the chamber and plane of movement of said contacts parallel to said base, said chamber and coils being located close to said 65 actuating means, and an armature pivoted on the same pivot as said movable contact operable by said electromagnetic means in response to predetermined overload conditions to cause said actuating means to open said contacts.

70 3. In a circuit breaker, a stationary contact, a

pivoted switch member cooperating therewith for opening and closing the circuit, actuating means for moving the switch member to open and to closed circuit position, electromagnetic blowout and trip means comprising a coil for 5 producing a magnetic field across the path of movement of the switch member to move and extinguish the arc drawn between the switch member and contact, and an armature pivoted about the same axis as said switch member movable by said electromagnetic means in response to predetermined overload conditions to cause said actuating means to move the switch member to open circuit position.

4. In a circuit breaker, a stationary contact, a 15 movable contact therefor carried by a pivoted switch member, actuating means for said switch member for moving the same to open and to closed circuit position, combined electromagnetic blowout and trip means including a pair of 20 aligned coils disposed on opposite sides of the path of movement of said movable contact for moving and extinguishing the arc drawn between said contacts, the axis of said coils extending transversely across the path of movement 25 of said switch member, and an armature pivoted about the same axis as said switch member for movement by said coils in response to predetermined overload conditions to cause said actuating means to move the switch member to 30 open circuit position.

5. In a circuit breaker, a stationary contact, a 35 cooperating movable contact carried by a pivoted switch member, actuating means for said switch member for moving the same to open and to closed circuit position, electromagnetic combined blowout and trip means including a pair of aligned coils disposed on opposite sides of the path of movement of said movable contact for moving and extinguishing the arc drawn 40 between said contacts, the axis of said coils extending transversely across said path, an armature pivoted about the same axis of said switch member for movement by said coils in response to predetermined overload conditions to cause said 45 actuating means to move the switch member to open circuit position, said armature having a pair of legs extending adjacent the outer ends of said coils for attraction thereby.

6. In a circuit breaker, a stationary contact, a 50 movable contact therefor carried by a pivoted switch member, actuating means for said switch member for moving the same to open and to closed circuit position, combined electromagnetic blowout and trip means including a pair of 55 aligned coils disposed on opposite sides of the path of movement of said movable contact for moving and extinguishing the arc drawn between said contacts, the axis of said coils extending transversely across the path of movement of 60 said switch member, and an armature pivoted about the same axis as said switch member for movement by said coils in response to predetermined overload conditions to cause said actuating means to move the switch member to open 65 circuit position, said stationary contact being secured to the leg of a T-shaped conductor, the free ends of the cross bar of said conductor being connected to the ends of said coils.
